Application April 28, 1931, Serial No. 533,416

22 Claims. (Cl. 68—18)

Our invention relates to a method of and apparatus for treating materials of various types, including textile materials and the like, such as clothing, garments, hosiery, household linen, natural and artificial silk, wool, cotton, and other fibrous and hair-like materials, or mixtures of one or more of them, either in the raw state or in wholly or partially manufactured state and in threads, yarns or skeins, in the form of cloth or 5 piece-goods, or in the form of fabrics or articles woven or knitted, and otherwise produced therefrom, skins, chamois, leather, pelts, furs, felt and the like; they are treated by laundering, washing, cleaning, scouring, dry cleaning, degumming, bleaching, dyeing or otherwise affecting them.

In accordance with our invention the material is treated by applying thereto or passing therethrough, preferably continuously, a suitable treating liquid, aerated to contain in large proportion 20 masses or bubbles of gas, generally air, of very small size, forming a mixture analogous to an emulsion of gas in liquid; the liquid is converted into foam comprising mist-like particles or bubbles, of small, extremely small or minute dimensions.

More particularly in accordance with our invention the treating liquid is withdrawn, preferably continuously, from a pool, and aerated or converted into foam or small bubbles applied to 30 the material to be treated while isolated from the pool of liquid, the aerated liquid, foam or bubbles passing into or through the material, with return to the pool of the de-aerated liquid or broken foam or bubbles; the aeration of the 35 liquid or its conversion into foam or small bubbles may be effected by any suitable means, preferably adjacent the material to be treated, or at a plurality of points or regions in the circulatory system.

Our invention resides also in apparatus, for effecting treatment of the character above described, comprising a container, for the material to be treated, having one or more perforated walls, a chamber for the pool of treating liquid, 40 a pump of any suitable type for withdrawing the liquid from the pool and delivering it to liquid-aerating or foam-generating structure, the liquid after operation upon the material returning through the aforesaid perforations to the pool; 45 more particularly, there is provided structure in or adjacent the pool for forming a preliminary mixture of air with the treating liquid, on the inlet or suction side of the pump, which then delivers a mixture of liquid with air to the aforesaid structure for further aerating the liquid or

further operating upon it in the generation of foam or fine bubbles.

Further in accordance with our invention, means, such as an electric heater, are provided for maintaining a suitably elevated temperature 5 of the treating liquid or the aerated liquid or foam; and more particularly the heater is disposed in the liquid circulating system, external to the pool and container for the material undergoing treatment.

Further in accordance with our invention the treating apparatus may comprise a centrifugal basket, having suitable outlets for liquid from its bottom, for holding the material during treatment while the basket is at rest. After treatment 15 the circulation of treating liquid may be discontinued and the basket revolved at suitably high speed for centrifugally wringing or drying the material.

Further in accordance with our invention, 20 either when the container is permanently stationary, or when it is a centrifugal basket as aforesaid, there may be additionally utilized paddles, vacuum cups or the like for agitating the material during application of the foam or aerated liquid.

When a spinner or centrifugal basket is employed as the container for the material or goods to be treated, the soapy water or other treating liquid after treatment thereby is preferably removed to a reservoir or storage tank, and water or the like introduced into the basket for breaking the remaining foam or bubbles therein and outside of it and below it, reducing the braking effect of the bubbles upon the basket and also 30 making it possible for centrifugally removing liquid from the treated goods, which is otherwise difficult or impossible with large quantities of bubbles or foam remaining in the basket. The water or liquid so introduced will serve also to 35 rinse the treated material, and into the rinsing liquid, or into liquid delivered into the basket after the first or final rinsing, may be introduced bluing or eventually starch. In accordance with 40 our invention, when utilizing a spinner or centrifugal basket for the container for the goods to be treated, the entire series of operations, commonly practiced in commercial and domestic laundering, may be effected in one and the same 45 container without removal of the goods until 50 dried to the extent usual or possible by centrifugal action.

Further in accordance with our invention, solid articles may be washed or otherwise treated in accordance with our method, and for such pur- 55

- pose apparatus of the character hereinafter described may be employed; particularly domestic dishes, utensils, table silver and the like may be washed by application of aerated liquid thereto, and then rinsed while remaining in the container in which washed, or upon removal therefrom. In accordance with another aspect of our invention there may be provided a cage of mesh or the like, containing suitable rack structure for holding dishes and the like, interchangeable with a centrifugal basket utilizable in the same machine for washing or otherwise treating clothing, household linen, and other textile materials and the like; and more particularly the cage may be oscillated or otherwise moved during treatment of the articles therein to insure complete application of the treating medium to all portions of the exposed surfaces of the dishes or other solid articles.
- Our present invention comprises features of method and structure disclosed in our prior application, Serial No. 448,114, filed April 28, 1930, and which has matured into Patent No. 1,948,568 granted Feb. 27, 1934, of which this application is in part a continuation.

For an understanding of our method and for an illustration of some of the various forms our apparatus may take, reference is had to the accompanying drawings, in which:

Fig. 1 is a vertical sectional view, partly in elevation, of treating apparatus embodying our invention;

Fig. 1a is a vertical sectional view, partly in elevation, on enlarged scale, of a part of the structure shown in Figs. 1 and 4 to 8 inclusive;

Figs. 2 and 3 illustrate some of the forms of liquid delivering means which may be utilized in lieu of the structure illustrated in Fig. 1a;

Fig. 4 is a vertical sectional view, partly in elevation, of another form of apparatus comprising a centrifugal basket;

Fig. 4a is a plan view of a modification;

Figs. 5 and 6 are vertical sectional views, partly in elevation, of other forms of our apparatus embodying paddles or means for agitating the material during treatment;

Fig. 5a illustrates a filter for use with the invention;

Figs. 7 and 8 are vertical sectional views, partly in elevation, of further forms of our apparatus in which agitation of the material is effected by vacuum cups;

Fig. 9 is a vertical elevational view, partly in section, of a cage for holding solid articles to be cleaned or otherwise treated;

Fig. 10 is a top plan view, partly in horizontal section, of the cage shown in Fig. 9;

Fig. 11 is a vertical sectional view, partly in elevation, of another form of our apparatus comprising a container, for the material to be treated, rotatable about a horizontal axis;

Fig. 12 is a horizontal sectional view, partly in plan, of the structure shown in Fig. 11;

Fig. 13 is a cross sectional view of the basket or container of Figs. 11 and 12;

Fig. 14 is a fragmentary view illustrating a motor drive.

Referring to Fig. 1, there is illustrated what may be termed for brevity a domestic or commercial washing, dry cleaning or laundering machine, utilizable however for treating materials in accord with other aspects of our method.

Within the stationary container or tub 1, preferably of sheet metal, supported upon legs or any other suitable means, not shown, is the removable

sheet metal false bottom or diaphragm 2, resting on members 2a and having perforations or holes 3 of suitable size, number and distribution, upon which is placed the clothing, garments or other material to be treated. It is provided with a removable cover 4, preferably of sheet metal, which is replaced in position shown after depositing the material to be treated upon the plate or bottom 2 within the chamber 1. Within the chamber 5, between the diaphragm 2 and the bottom 6 of the container 1, is a pool 7 of suitable liquid, such as an aqueous solution of soap or equivalent for ordinary washing or laundering, but which may be of a character suitable for other types of treatment as herein-after described.

In the bottom 6, preferably in the depression or sump basin 8 thereof, is an outlet opening 9 communicating through the hose connection 10 with the pipe 11 delivering into the suction 20 chamber or inlet 12 of a pump 13, of any suitable type. In the example illustrated and preferably, the pump 13 is of the rotary, centrifugal or impeller type having the rotor or impeller 14, driven at suitably high speed by any suitable means such as the electric motor 15, of constant or variable speed as may be desired. The pump withdraws liquid from the pool 7 and delivers it at higher pressure through the hose connection 16 to the pipe 17 communicating with the lateral 30 pipe 18 upon the upwardly extending pipe 19 having at its upper end the slip connection or union 20 through which extends into the interior of the pipe 19 the vertically adjustable pipe 21 having at its upper end the rotatable 35 valve 22 whose rotating element is secured to and is rotatable with the laterally or inwardly extending pipe 23 having the downwardly directed exteriorly screw-threaded end portion 24, upon which is threaded a washer 25 between 40 which and the nozzle member 26, also threaded upon the pipe end 24, is confined the bell or cup shaped member 27 of rubber or other suitable material loosely and detachably fitting over the upwardly turned annular lip or flange 28 upon 45 the cover 4, to form a detachable yet liquid or foam-tight connection with the interior of the chamber 1. With the pipe 23 and other parts in the position shown the valve 22 is open, permitting continuous delivery of fluid by the pump 50 13 through the pipe 23 into the passage nozzle 26a within the nozzle member 26. The cross section of this passage throughout its length may be uniform and preferably, as illustrated, it is divergent toward its discharge end. Within this 55 passage and at or adjacent the end of the pipe 24 is a transversely extending member 26b, secured to or integral with the nozzle member 26. Against the member 26b is held by the screw 29 the nozzle element 30 whose external diameter 60 may vary longitudinally of its axis in any suitable way. In the example illustrated the external diameter first increases, to the constriction or throat 31 in the nozzle passage 26b, then decreases, and then finally again increases in 65 diameter. Between the exterior of the member 30 and the wall of the passage 26a is formed an annular nozzle passage which is first convergent to the throat 31 and then divergent to the outlet. Extending upwardly in the member 30 is a passage 30a open at the lower end of the member 30 which terminates in the flange or member 31. From passage 30a there extend outwardly and preferably downwardly in the direction of liquid flow from the pipe 24 several air passages 32 dis- 70

tributed or spaced circumferentially of the member 30.

Liquid from the pool 7, or liquid mixed with gas or air as later described, is delivered by the pump through the nozzle passage 26a around the member 30, and in so passing, at or near the throat 31 there is drawn in and entrained air entering through the several air passages 32. The rate of delivery of liquid or liquid and air, controllable by the speed of impeller 14, and the rate of admixture of air are preferably such that the liquid becomes well or highly aerated, containing innumerable small or extremely fine or minute masses or bubbles of air, rendering the mixture discharged from this foam generator or aerator practically a foam of very small bubbles or a liquid and air emulsion, the liquid being the outer or continuous phase with respect to the minute particles, masses or bubbles of air. The size of the bubbles or air masses is preferably very small, mainly or wholly less than one-half inch diameter, and largely or wholly less than $\frac{1}{8}$ " in diameter, ranging down to minute globules, bubbles or sacks of air of the order of one to several hundredths of an inch, and preferably mainly of even smaller orders of magnitude.

The foam or aerated liquid is discharged on to the top of the material to be treated, enters, permeates or penetrates it, effecting most rapid and highly efficient laundering or cleansing of the fabrics or other material treated.

There is developed or exists a difference in pressure between the region above the material treated and the region in the vicinity of the bottom 2 or in the chamber 5. This difference in pressure facilitates permeation of the material by the aerated liquid or foam, causing it to pass more or less completely through the material, emerging therefrom at the bottom and around the sides as liquid, or to some extent foam, or partially aerated liquid. The liquid loses its air or the foam condenses into liquid, and as such passes through the perforations 3 into the pool 7 from which it is continuously recycled, and in each cycle becomes aerated or converted into foam or fine bubbles.

While liquid aerating or foam generating structure of the type described is highly efficient, any other suitable form of injector, ejector or jet apparatus may be utilized; or there may be utilized any other suitable type of liquid discharge structure.

For this purpose there may be used upon the end of the pipe 24 as indicated in Fig. 2, a spray nozzle or rosette 33. In discharging therefrom the liquid becomes more or less aerated or converted into foam or bubbles. The cover 4 in this case is provided with an aperture 4a, large enough for insertion of the structure 33, and fitting the exterior of the pipe 24 and the cover 4 is a closure member 27a of rubber or other suitable material.

Or as indicated in Fig. 3 the pipe 24 may discharge liquid directly into the interior of the chamber 1, becoming somewhat aerated or to a degree converted into foam, the aeration or foam generation being further enhanced by impacts of the liquid upon the material to be treated.

The cover 4 is provided with an aperture 4a through which the pipe 24 loosely extends. There may also be provided a closure member or washer 27b of rubber or other suitable material.

Whatever may be the character and mode of operation of the structure discharging liquid from

the pipe 23 into the container 1, there may be and preferably is used also further structure for causing admixture of air with the treating liquid from pool 7. Such structure may be of any suitable type or form; in the example illustrated it comprises a member 34 joined by circumferentially spaced ribs or plates 35 with the member 36 having the downwardly extending tubular outlet 37. A tube 38, whose upper end is disposed above the liquid 7 in the air space in the chamber 5, is attached to the member 34 and communicates at its lower end with the interior of the structure. As liquid is drawn through the space between the ribs 35 inwardly and downwardly through the discharge element 37, air from the chamber 5 passes downwardly through the tube 38 and within the structure, and within the pump 13, comes into mixture with the liquid, to some extent aerating it or converting it into bubbles or foam. However, the density is such that it is readily acted upon and raised in pressure by the pump impeller 14 whose speed is suited to the purpose. The mixture of liquid and air is passed through the pipes 17, 19, 21 and 23, and is discharged into the container 1 through whatever type of structure may be applied to the end of the tube 24, or directly from the tube 24, as in Fig. 3, into the chamber 1. In the example illustrated the mixture of air and liquid is discharged from the pipe 24 through the nozzle structure 26 within which more air is drawn in by aspiration or injector action and delivered into the nozzle passage 26a through the several passages 32, increasing the amount of air contained in the liquid, thereby completing the foam generation or aeration of the liquid.

Withdrawal of liquid from pool 7 and/or air from chamber 5 by the pump 13 reduces the pressure in chamber 5 or on the underside of the goods undergoing treatment, producing or assisting in producing that pressure difference on opposite sides of the goods which enhances passage of the liquid and gas or air into or through them.

For some processes including commercial and domestic laundering of fabrics, clothing, house-hold linen and the like, it is desirable that the liquid be maintained at elevated temperature. For this purpose heat may be continuously imparted thereto by any suitable means. For this purpose there is inserted through the lower end of the pipe 19 an electric heater unit 39 whose lower end is provided with a plug or enlargement 39a which forms a liquid tight joint with the pipe 19, preventing leakage of the circulating liquid. This heater may be of any suitable type, generally a resistance, heated by the current traversing it and led thereto through the terminals 39b and 39c to which are connected the conductors 40 and 41, connecting to an electric supply circuit through any suitable switch, which may also simultaneously control supply of current to the pump motor 15.

When the heater is disposed in the position indicated, heat is continuously delivered to the liquid during circulation by the pump 13.

Upon completion of treatment of the material within the container 1, the tube 23 may be rotated about the center of the valve 22 to vertical position closing the valve and stopping circulation of liquid. The cover 4 is then removed and the container 1 emptied and recharged with another batch of clothing or other fabrics. The pipe 23 is then restored to the position indicated with the member 27 making connection with the

flange 28 upon the cover 4 and the process repeated.

When the apparatus is no longer to be used, the pipe 23 may be swung outwardly, in which case the valve 22 is again open, and the liquid discharged to waste as into a sink or any other suitable receptacle D connected to sewer or in which the liquid is to be stored for future use. To permit the discharge end of the pipe 23 to reach sinks or receptacles of different heights, the pipe 21 may be raised or lowered in the pipe 19 through the loose but liquid-tight union 20. The liquid not so discharged, and the dregs from sump basin 8, may be drawn off through cock 42. In Fig. 4, the structure is in principle the same. In this case there is provided a removable spinner or centrifugal basket 45 carried upon and driven by the shaft 46 extending freely through the tube 47 attached to the bottom 6 of the container 1 and reaching above the level of the liquid pool 7. Beneath the bottom 6 is provided any suitable driving means, such as an electric motor, which may be or serve as the motor 15 for driving the pump 13. Under such circumstances there is provided suitable means, well known in the art of washing machines of this general character, for coupling the motor rotor or armature to the shaft 46; the impeller 14 may be continuously driven by motor 15 or through coupling means of the character aforesaid.

For purposes later described, it is preferred that there be provided a storage tank or reservoir having capacity sufficient for storing the soapy water or other treating liquid of the pool 7. The reservoir or storage tank may be separate; preferably, however, it is comprised in the washing or treating machine unit. In the example illustrated by Fig. 4 the extra storage tank 1a is formed by the casing wall 1 and the sheet metal wall 1a spaced therefrom. In this instance the extra storage tank 1a is itself cylindrical within the cylindrical wall 1.

This auxiliary tank 1a may be provided with cover 1b which, at a point to which the discharge of the pipe 23 may be swung, may have an opening for discharge from the pipe 23 into the auxiliary tank of the liquid pumped from the pool 7. At or adjacent its lower end the tank 1a is provided with a pivoted valve V operable by the rod r extending to the exterior where it is provided with a handle h.

It will be understood, however, that the auxiliary tank 1a may take any suitable form and be disposed in any suitable arrangement. In the example illustrated in Fig. 4a the storage tank 1a is in the form of an outer structure, extending part way around the casing wall 1 which with the wall 1a forms the storage tank which may be provided with a cover, having an opening 1c to which the aerator or discharge end of pipe 23 may be swung to discharge the liquid from the pool 7 into the tank 1a. This tank will also be provided with a valve V, controlled by handle h, controlling communication between the tank 1a and the pool 7 or bottom portion of the casing 1.

In this case the clothing, fabric, or the materials to be treated are deposited within the basket 45 which remains at rest during the application of aerated liquid or foam, as described in connection with Fig. 1. Besides the holes or apertures 48 in the side or circular wall of the basket 45, through which liquid is thrown when the basket is rotated at high speed for wringing

or drying, there are provided in the bottom 45a of the basket 45, the holes or apertures 49. The liquid after contact with or penetration of the material with the basket stationary, drains out through the holes 49, and thence directly into the pool 7, if the false bottom or diaphragm 2 be omitted, or when present, as illustrated, through the holes 3 therein. In the bottom 2 may be provided a stuffing box or gland 50 in which the shaft 46 runs freely.

In circulating liquid from and back to pool 7, and aerating it for treatment of the material within the stationary basket 45, there generally obtains the condition, at the end of such a run, that the interior of the basket is filled with bubbles or foam, and the same is true of the space surrounding the basket and above the pool 7.

The foam and bubbles may be broken by introduction of water or suitable liquid into the basket, but this would involve addition of water or the like to the pool 7, which is sometimes undesirable particularly where the treating liquid, as soapy water or the like, is not to be diluted and is to be saved for re-use.

After the material in the basket has been suitably treated by the aerated liquid from the pool 7 it is difficult, if not impossible, to break or throw out the foam or bubbles from the basket when rotated at high speed. Furthermore, the foam or bubbles contacting with the exterior of the basket and the outer side of its bottom, exert a substantial braking effect upon the basket, slowing its speed below that desirable or requiring a larger motor for driving it through the shaft 46. In addition, the foam or bubbles in which the basket is so immersed reduce the weight of the basket and its contents exerted downwardly through the shaft 46, thereby lessening the rotative driving force applied to the basket through a clutch or driving mechanism which depends upon the weight of the basket and its contents for effectively driving the basket.

To overcome these disadvantages, and to make it possible promptly to centrifugally dry the material within the basket, the valve V is placed in its closed position illustrated in Fig. 4, the aerator or discharge end of the pipe 23 is swung into position over the opening in the auxiliary tank cover 1b, and all of the liquid of the pool 7 is delivered by pump 13 into the auxiliary tank 1a, where it is stored so long as the valve V remains closed. Thereupon, through the now open aperture 28 in the cover 4, or upon removal of the cover 4, water or other suitable liquid is delivered into the basket 45, preferably in a spray as may be afforded by rosette or sprinkler R connected through a hose to either a hot or cold water spigot S, as shown in Fig. 5. The foam or bubbles are in consequence condensed into liquid or broken, and while the basket 45 is rotating at high speed, the liquid will be thrown out through the basket perforations and passed to the bottom of the casing formerly occupied by the pool 7, from which the liquid there collecting is discharged under the operation of the pump 13, through the outlet of the pipe 23 swung over a sink D or other waste. Delivery of water into the basket may be discontinued at any suitable time after condensation of the foam or bubbles, whereupon the material within the basket is dried, so far as possible, by centrifugal action. The condensation of the foam or bubbles permits centrifugally wringing the material within the basket, removes the braking effect otherwise applied to the basket, and eliminates the lifting

effect upon the basket and its contents thereby causing them to be positively driven at a suitably high speed.

After first centrifugally drying the material in the basket, or immediately after or as a continuation of application of water to break the remaining bubbles or foam, rinsing water may be delivered into the basket, fully to submerge the material therein, if desired, and the material therein agitated either by hand or by agitating structure such as paddles or vacuum cups of the character hereinafter referred to in connection with other figures. The water so applied may then be delivered to a sink or waste D by pump 13 through pipe 23 which immediately before may have been in position to close valve 22 to allow accumulation of water within the basket to suitable height.

To the water introduced into the basket at any stage after the initial washing operation by the aerated liquid, may be added bluing or other material for bluing or otherwise affecting the clothes or other material; and similarly starch may be introduced into the water within the basket at suitable stage, the bluing and starch water eventually discharged to waste by pump 13 through pipe 23 which will then be swung to horizontal position to open the valve 22 over sink or drain D.

In consequence, when a centrifugal basket is employed, the material may be completely laundered, washed or treated before removal from the basket. When finally centrifugally dried, the goods or material are withdrawn from the basket and dried upon a clothesline or otherwise artificially completely dried.

For the next run, after all liquid has been discharged from the space at the bottom of the chamber formed by the internal wall 1a, the valve V is retained in open position, by suitable operation of the handle h, causing the soapy water or other treating liquid to return from storage tank 1a into the bottom of the chamber formed by the wall 1a, there accumulating again as the pool 7. Upon restoration of the cover 4 and the return of the aerator or discharge end of the pipe 23 to the position shown in Fig. 4, the cycle of operations is repeated.

The storage chamber 1a, particularly when empty or while liquid is circulated from and to pool 7 and aerated, serves to conserve the heat in the liquid or applied thereto as by heater 39.

In Fig. 5 the arrangement is generally similar to that of Fig. 4 and the mode of operation is substantially the same. There are provided in addition, however, the agitating elements or paddles 51 of suitable number and circumferentially spaced; they are secured upon and oscillated through suitable angle by the inner oscillator shaft 52, to which they are connected through the sleeve 53. With the basket 45 at rest, and during the treating operation involving the recycling of liquid from and back to the pool 7, the paddles 51 by their rotary oscillation agitate the goods within the basket, speeding and improving their treatment. After the liquid is drained through the holes 49 back into the pool 7, the basket is driven at high speed for centrifugal wringing or drying, by the outer hollow shaft 54 to which it is removably secured.

In Fig. 5a there is shown an adjunct, a filter F, which may be utilized in connection with any of the forms of the apparatus contemplated by our invention and as illustrated in Figs. 1 and 4 to 9 inclusive. A description thereof in connec-

tion with Fig. 5 will suffice for all the other figures aforesaid.

Within the filter casing 55, having a removable wall, as the cover 56, is a bag or cartridge 57, having porous walls, within which is disposed a filtering material, suitable to the treating material employed. The liquid circulated by the pump 13 and delivered into the top of the container 1 is passed into and through the filter through the pipe 19 and passes out to the valve 22 and pipe 23 through the pipe 19a. From the pipe 19 there is a by-pass pipe 19b around the filter to the valve 22. By opening the valve 58 the liquid is by-passed or circulated in the system without passing through the filter, which for this operation is cut out by closing the valve 59. When the valve 58 is closed and the valve 59 is open, the treating liquid passes through the filter.

A filter is particularly desirable for dry-cleaning purposes in which case the liquid in the pool 7 which is recycled, is carbon-tetrachloride, naphtha, gasoline or equivalent. During circulation of the liquid it is purified in the filter by removal therefrom of grease and other materials that have been dissolved therein or physically transported thereby. For dry-cleaning liquids of the character indicated, the filter medium may be fuller's earth, or equivalent.

It will therefore be understood that the filter may be connected in the circulating system of any of the apparatus contemplated by our invention and as herein illustrated; or, and as more specifically illustrated, it may be employed in connection with a by-pass system, so that the liquid circulated may be filtered or not, as desired.

For dry-cleaning purposes, liquids of the character above specified may be utilized in any of the apparatus contemplated by our invention and various forms of which are illustrated.

In the arrangements employing a spinner or centrifugal basket 45, (Figs. 4, 5) the bottom and a portion of the side above the bottom of the basket may be devoid of perforations. The pump 13 delivers the dry-cleaning liquid from the pool 7 through the pipe 23 into the basket, as through a simple pipe opening as illustrated in Fig. 3, without aeration, thereby producing a pool of cleaning liquid in the basket. Or the aforesaid lower portion of the side wall and/or the bottom of the basket 45 (Figs. 4, 5) may have a few or small perforations through which liquid returns to pool 7 at a rate less than the rate of discharge of liquid into the basket from pipe 23, whereby a pool is maintained in the basket. Through these perforations, especially those in the basket bottom, may escape solids and semi-solids removed from the material.

The liquid is circulated from and back to the pool maintained in the basket long enough to effect the necessary cleaning of the material within the basket which is stationary. The liquid pool in the basket rises to a level up to the lowermost row of perforations, wholly or partially submerging the material. After completion of the treatment, the basket is driven at high speed, and the liquid in the bottom of the basket drains out or rises up along its side under the influence of centrifugal force and is thrown out through the perforations in the side of the basket and returns to the pool 7; and liquid is centrifugally extracted from the material and returned to pool 7. During the spinning action, the pipe 23 is raised to position closing the valve 25.

22, leaving the cover aperture 28 open, while the cover 4 is in place. During the spinning of the basket a vortex is formed; due to the zone of reduced pressure or partial vacuum at the center 5 of the vortex, a current of air is drawn in through the aperture 28 in the cover, and in descending forces the gases, heavier than air, which have separated from the liquid, downwardly to the pool 1 where they are reabsorbed. 10 The spinning of the basket, as usual, removes the major part of the liquid from the goods which are then ready to be finally dried, either upon a clothesline or the like, or by artificial means. 15

When using dry-cleaning liquid, the heater 39 may be employed or not, as may be desired.

In Fig. 6, the arrangement is generally similar to that of Fig. 1, except that the false bottom or diaphragm 2 is preferably conical with the apex 20 at the axis of the shaft 52 which oscillates the paddles or agitating members 51, whose lower edges conform generally to the incline of the bottom 2. As indicated, there may be attached to the casing 1 or to other suitable part of the apparatus, the manually or motor driven wringer 25 60 comprising as usual two rollers pressed toward each other. It will be understood that such a wringer may be applied also to the form illustrated by Fig. 1, or in any case where a centrifugal basket is not present.

In Fig. 7 there is again provided a centrifugal basket 45 having perforations in its side and bottom. It is mounted upon and rotated by the outer shaft 54, generally described in connection 35 with Fig. 5. Upon the inner shaft 52 are secured the arms 61 carrying the vacuum cups 62 which are reciprocated upwardly and downwardly by the shaft 52, and also rotated to different angles about the axis of the shaft 52, for agitating the goods during treatment by the 40 circulating liquid from pool 1; the vacuum cups alternately lifting and depressing the goods. With a vacuum cup system as commonly employed in a washing machine in which the goods 45 are immersed in the washing solution, the upward strokes of the vacuum cups are more important in the agitation effected than the downward strokes. In connection with our process, however, the vacuum cups are about equally 50 effective in their upward and downward strokes, when used in accordance with our method, characterized by the fact that the goods are isolated from the pool of liquid and are subjected to treatment by foam or aerated liquid only.

In Fig. 8 is shown a modification without centrifugal basket, generally similar to Figs. 1 and 6. In this case, the goods lie upon the false bottom or diaphragm 2 and the vacuum cups are operated by shaft 52, upwardly, downwardly, 55 and circumferentially.

In apparatus of the character hereinbefore described solid or non-porous articles, such as household dishes, utensils, table silver and the like may be washed or cleansed by applying thereto aerated liquid, such as soap solution, while substantially isolated from a mass or pool of liquid. For this purpose the dishes or other solid articles may be disposed in the chamber above the false bottom 2 in Figs. 1, 6 and 8, with the agitating structure 51 or 62 of Figs. 6 and 8 at rest or removed; or they may be disposed in the basket 45 of Figs. 4, 5 and 7 while the basket is stationary, and in the case of Figs. 5 and 7 while the agitating structure 51 or 62 is at rest 60 or removed. The solid articles, dishes or the

like are suitably arranged within the chamber or basket, or suitably disposed upon racks or frames in the chamber or basket, to allow contact therewith of the aerated liquid throughout substantially their entire exposed surfaces. 5

Preferably, however, the solid articles, dishes or the like are disposed in a cage of wire mesh or the like interchangeable with the removable basket 45 of Fig. 4, 5 or 7.

One of various suitable forms of cage structure 10 is illustrated by Fig. 9, of which Fig. 10 is a horizontal sectional view, taken on the line 10—10 of Fig. 9. The cage 45a, open at its top, comprises a cylindrical or other suitably shaped wall 45b and bottom 45c of wire mesh, expanded metal, 15 perforated sheet metal, or equivalent. The meshes or apertures in the bottom 45c are preferably smaller than those of the side wall 45b, to retain solids or semi-solids washed from the dishes or solid articles. The upper end of the side wall 20 45b is attached to the metal ring 45d. Within the cage are provided a suitable number of suitably spaced rack or holder members of wire mesh or equivalently apertured elements 45e, of different 25 lengths, disposed, for example, on opposite sides of the diametrically or otherwise positioned member 45f, which also may be of wire mesh or equivalent, and extending to the wall 45b to which they are suitably attached by welding or otherwise. At their inner ends they are welded or 30 otherwise attached to the member 45f, and the latter and the members 45e are preferably attached or welded to the bottom 45c. Secured by 35 welding or otherwise to the bottom 45c, or to several of the rack members 45e, or to the member 45f, or to all of them, is the round hollow shaft or sleeve 46a whose upper portion is the solid member or stub shaft 46b beneath which may be provided splines engaging with splines 46c on the upper end 40 of the basket driving shaft 46, Fig. 4.

The cage is interchangeable with the basket 45 of the machine illustrated by Fig. 4. Upon removal of the basket 45, the cage 45a is substituted for it, the sleeve 46a, corresponding with the basket sleeve 46a of Fig. 4, passes over the upper 45 end of the shaft 46, and the stub shaft 46b rests upon the upper end of the shaft 46. Or, if the spline structure 46c is provided, the splines of the cage sleeve engage those on the shaft 46. In any event, the cage is supported practically in the position formerly occupied by the basket 45, and into its spaces 45g of various sizes and shapes, formed by the members 45e, and by some of them and the wall 45b, are deposited the dishes, utensils, silverware or other solid articles to be treated or 55 cleaned. The cover 4 and the aerator, which generates the foam or bubbles, are returned to positions indicated in Fig. 4 and the soapy water or other treating liquid is circulated from and back to the pool 1, the foam or aerated liquid passing through the spaces between the solid articles, cleansing them; the liquid passes through the cage meshes or apertures and returns to pool 1 for recirculation. 60

After the cleansing operation, the liquid of the pool 1 may be discharged to waste or to storage tank 1a if it is to be used again. There can then be introduced, upon removal of the cover 4 and the aerator, water, preferably hot, for rinsing the solid articles and dishes, the rinsing water collecting in the bottom of the container and then discharged by the pump 13 to the sink D, or elsewhere. 70

The cage 45a may similarly displace the basket 45 in the structure of Figs. 5 and 7, the paddles 51 75

or vacuum cups 62 having been removed prior to removal of the basket. The sleeve 46a of the cage is then slipped over the outer or basket driving shaft 54 which remains at rest. Or the cage may be provided with structure for supporting or securing it upon the inner or agitator shaft 52, and that shaft may remain at rest or be rotatably oscillated as described in connection with the paddles 51 of Fig. 5, to move or oscillate the cage at suitable slow speed during application of the aerated liquid more uniformly and thoroughly to distribute the foam over the dishes or solid articles.

By providing a cage, interchangeable with a spinner or centrifugal basket in machines of the general character illustrated by Figs. 4, 5 and 7, there becomes available, particularly for domestic use, and especially for confined quarters such as apartments, a combined laundering and dish washing machine by which table dishes, utensils and the like may be washed by and in the same method and system in which clothes and the like may be completely laundered by washing, rinsing, bluing, starching and the like, without removal of the clothes from the basket. To provide for washing of dishes and like articles, there is required in addition only a cage of the general character above described.

When employing the cage, in lieu of the centrifugal basket, for washing dishes and the like, maintenance of elevated temperature is particularly desirable, and this, as before, is accomplished by the electric heater 39 which delivers heat to the liquid circulated from the pool 7.

In Figs. 11-13, the container for the material or goods to be treated is a cylinder 63 disposed in the casing or chamber 1, in the bottom of which is the pool 7 of treating liquid. The cylindrical wall comprises the perforated arcuate elements 64 and the perforated arcuate covers 65 slideable about the axis of the cylinder over the elements 64 to form openings through which the goods or material to be treated are charged into and removed from the interior which may be suitably divided by walls or diaphragms 66, perforated or not, as may be suitable or desirable. The end walls 67 may be perforated or not. The cylinder is mounted upon a hollow perforated shaft 68 having a bearing at its one end at 69 and at its other end at 70. The treating liquid as before is withdrawn from the pool 7 by the pump 13 and delivered to the pipe 19, which again may be provided with electric heater 39, to the nozzle 71 which discharges a jet of liquid containing air when the structure 38, 34 is utilized, entraining air entering through the holes 72, aerating the liquid or producing foam which is discharged through the passage 73 to the interior of the hollow shaft from which it escapes through the perforations of the shaft and passes radially outward, under a difference of pressure, through the goods or material within the compartments of the cylinder 63.

During operation the cylinder 63 is continuously rotated in one direction or oscillated as may be desired. For driving the cylinder 63 there is provided a motor M, Fig. 14. The motor M, through reducing gearing, comprising a gear 74, worm 75, shaft 76, worm 77, gear 78, shaft 79, and worm 80, drives the gear 81, which in turn actuates the connecting rod or pitman 82 which rotates or oscillates the gear 83 which drives the pinion 84 upon the shaft 85 to which is coupled the shaft 68 of the cylinder or basket 63.

At the end of a run, the slides 65 are opened in

succession, by access through the opening 86 of the casing 1 having the removable cover 87, and through this opening goods or material to be treated are removed from the several compartments of the cylinder 63 in succession.

The apparatus illustrated in Figs. 1 to 8 inclusive, is of a form and type utilizable as a domestic cleaning or washing machine, and is generally of moderate size, though it will be understood that the size is not a feature of our invention and that apparatus of this character may be constructed of any suitable size, for commercial cleaning, laundering, and the like.

Structure of the character illustrated in Figs. 11-13, comparable to the system and structure illustrated in Figs. 2-5 of our aforesaid application Serial No. 448,114, is generally constructed in larger sizes for commercial laundries, cleaning and dyeing establishments.

It shall be understood, as disclosed in our aforesaid application, the treating liquid besides carrying soap or equivalent for washing or laundering purposes, may carry dye, particularly when the apparatus is used in washing and dyeing establishments, though it may be utilized also in connection with domestic washing and cleaning machines.

It will further be understood that the gas which aerates the liquid, or forms the bubbles or foam, may be other than air, and of a character to effect a treatment of the goods or materials, as by bleaching or otherwise affecting them, as described in our application aforesaid.

It will be further understood that our method and apparatus are utilizable for de-gumming dyeing silks either raw, in skeins, yarn, piece-goods, or manufactured articles, including hosiery.

For brevity in the appended claims, the term "air" is employed in a generic sense to include air or other gas or vapor, or a mixture of them; and reference in the claims to aeration is synonymous with and comprehends production of foam or bubbles by combining or mixing air or other gas, or mixture of them, with liquid.

What we claim is:

1. The method of treating material, which comprises withdrawing liquid from a pool thereof, from contact with which the material to be treated is substantially isolated, passing the liquid in mixture with air to a region between which and said pool said material is disposed, there further aerating the liquid, applying the aerated liquid to said material, and returning the liquid after contact with said material to said pool.

2. The method of treating textile material and the like with a liquid, which comprises withdrawing air from a region charged with the vapor of liquid by which the material is being treated and passing the charged air with said liquid to another region adjacent and in communication with said material, there further aerating the liquid, and causing the aerated liquid to penetrate the material under the influence of a difference between the pressures existing in said regions.

3. The method of treating material, which comprises confining the material in a substantially closed chamber out of contact with a pool of liquid therein, withdrawing liquid from said pool, withdrawing air from the space above said pool and passing it with the liquid withdrawn to a region between which and said space said material is disposed, there further aerating the liquid, and applying the aerated liquid to said material.

under the influence of a difference between the pressures in said region and space.

4. The method of treating textile material and the like, which comprises withdrawing liquid from a pool thereof, from contact with which the material to be treated is substantially isolated, withdrawing air from a region charged with the vapor of liquid by which said material is being treated, and passing the charged air with the liquid withdrawn from said pool to another region adjacent and in communication with said material, there further aerating the liquid, causing the aerated liquid to penetrate the material under the influence of a difference in pressure existing between said second and first named regions, and returning the liquid after its contact with said material to said pool.

5. The method of treating material, which comprises confining the material in a substantially closed chamber out of contact with a pool of liquid therein, withdrawing liquid from said pool, withdrawing air from the space above said pool and passing it with the liquid withdrawn from a region between which and said space said material is disposed, there further aerating the liquid, applying the aerated liquid to said material under the influence of a pressure difference existing between said region and said space, and returning the liquid to said pool after its contact with said material.

6. The method of treating textile material and the like, which comprises continuously supplying liquid in mixture with air to a region on one side of the material, there further aerating the liquid, and maintaining a region of lower pressure to draw the aerated liquid through said first named material from said region to said region of lower pressure.

7. The method of treating textile material and the like, which comprises continuously supplying liquid in mixture with air to a region on one side of the material to be treated, there further aerating the liquid, maintaining a region of lower pressure to draw the aerated liquid through said material from said first-named region to said region of lower pressure, and applying heat to the circulating liquid.

8. Apparatus for treating material comprising a receptacle therefor, a liquid aerator comprising a member having a passage, a second member disposed in said passage and spaced from said first named member to form an annular nozzle passage, means for continuously delivering liquid to said first named passage from said receptacle, said second named member having passages in communication with said receptacle for delivering air from said receptacle into said nozzle passage from which foam is discharged into contact with the material to be treated.

9. Apparatus for treating material comprising a receptacle therefor, a receptacle adapted to contain a pool of liquid and in communication with said first-named receptacle, means for continuously circulating liquid from said pool and discharging it to said material from which it returns to said pool and is recirculated, and means for delivering air into said circulating liquid from a region, said material being disposed between said region and the region of discharge of said liquid to said material.

10. Apparatus for treating material comprising a receptacle therefor having a perforated wall isolating said material from a pool of liquid, a liquid aerator disposed to discharge into said receptacle, means for continuously circulating

liquid from said pool to said aerator, and means for admixing air with the liquid flowing to said aerator.

11. Apparatus comprising a receptacle for material to be treated and adapted to contain a pool of liquid therein, means for isolating said material from said pool of liquid, means for continuously circulating liquid to the material from and back to said pool, means for aerating the liquid applied to said material, and means for heating said liquid.

12. Apparatus for treating material comprising a receptacle therefor, an aerator delivering aerated liquid to said material, means for continuously delivering liquid to said aerator, means for continuously admixing air with the liquid delivered to said aerator, and means for applying heat to the liquid.

13. Apparatus for treating material comprising a container therefor and adapted to contain a pool of liquid, perforated structure separating said material from said pool, a pump and conduit for circulating liquid from said pool to said material, and means on the suction side of said pump for admixing the liquid with air withdrawn from a region within said container charged with vapor of said liquid.

14. Apparatus for treating material comprising a container therefor and adapted to contain a pool of liquid, perforated structure separating said material from said pool, a liquid aerator, a pump and conduit for circulating liquid from said pool to said aerator for delivery of aerated liquid to said material, and means on the suction side of said pump for admixing with the liquid air withdrawn from a region within said container charged with vapor of said liquid.

15. Apparatus for treating textile material and the like comprising a container and adapted to contain a pool of liquid, stationary perforated structure isolating said material from said pool and permitting flow of liquid to said pool, means for agitating the material, a liquid aerator delivering aerated liquid into contact with said material, and means for continuously circulating liquid from said pool to said aerator and recirculating the liquid returned to the pool through said perforated structure.

16. Apparatus for treating textile material and the like comprising a container adapted to contain a pool of liquid, a normally stationary basket having perforated side and bottom walls disposed above said pool for containing said material, a liquid aerator above the material in said basket, means for continuously circulating liquid from said pool to said aerator and for recirculating the liquid returned to said pool through said perforated side and bottom walls, and means whereby said basket may be rotated after discontinuation of liquid circulation for removing liquid remaining in said material.

17. Apparatus for treating textile material and the like substantially solely by aerated liquid comprising a container adapted to contain a pool of liquid, a normally stationary basket having perforated side and bottom walls disposed above said pool and containing said material, a liquid aerator above the material in said basket, means for continuously circulating liquid from said pool to said aerator, means for rotating said basket after discontinuation of liquid circulation for removing liquid remaining in said material, and means within said basket for agitating said material during circulation of the liquid.

18. Apparatus for treating textile material or

75

the like substantially solely by aerated liquid comprising a container adapted to contain a pool of liquid, a normally stationary basket having perforated side and bottom walls disposed above said pool and containing said material, a liquid aerator above the material in said basket, means for continuously circulating liquid from said pool to said aerator, means whereby said basket may be rotated after discontinuation of liquid circulation for removing liquid remaining in said material, and paddle structure mechanism agitating the material within said basket when stationary and while said material is surrounded substantially solely by aerated liquid.

19. Apparatus for treating textile material and the like substantially solely by aerated liquid comprising a container adapted to contain a pool of liquid, a normally stationary basket having perforated sides and bottom walls disposed above said pool and containing said material, a liquid aerator above the material in said basket, means for continuously circulating liquid from said pool to said aerator, means whereby said basket may be rotated after discontinuation of liquid circulation for removing liquid remaining in said material, and vacuum cup structure for agitating the material within said basket while stationary and while said material is surrounded substantially solely by aerated liquid.

20. The method of treating material which comprises continuously circulating liquid in a path including a treating zone containing said material, generating foam by admixture of a fluid with said liquid for application to said material for treatment substantially solely by foam, effecting passage of the foam and constituents

thereof through said material by maintaining reduced pressure beyond said zone, subsequently passing liquid through said zone without generation of foam to condense foam remaining in the material, and rotating said material in said zone 5 to extract the liquid and condensed foam by centrifugal action.

21. The method of treating material which comprises continuously circulating liquid in a path including a treating zone in which said material 10 is disposed, generating foam by admixture of a fluid with said liquid for application to said material for treatment substantially solely by foam, effecting passage of the foam and constituents thereof through said material by maintaining reduced pressure beyond said zone, diverting said liquid to a reservoir, introducing and passing another liquid through said zone without generation of foam to condense foam remaining in the material, removing said second liquid, and re- 15 returning said first liquid for circulation in said path for treatment of another batch of material.

22. Apparatus for treating material substantially solely by aerated liquid comprising a container therefor adapted to contain a pool of liquid, 25 perforated structure isolating said material from said pool, a liquid aerator for delivering aerated liquid to said material, and means for circulating liquid from said pool to said aerator, said perforated structure permitting return of 30 de-aerated liquid to said pool, and ensuring that said material is treated substantially solely by aerated liquid.

LEON DE R. FABER.
CHARLES J. CARROLL. 35
